CONVECTIONAL COOLING COVER FOR MECHANICAL SPEED CHANGERS AND THE LIKE

Walter R. Woodward, Carlisle, Mass., assignor to United Shoe Machinery Corporation, Boston, Mass., a corporation of New Jersey

Filed Jan. 11, 1965, Ser. No. 83,377

Term of patent 14 years

(Cl. D55—1)

Fig. 1

Fig. 2

*Fig.3*FIG. 1 is a view in front elevation of a convectional cooling cover for mechanical speed changers and the like, showing my new design, and

FIG. 2 is a view in side elevation thereof.

FIG. 3 is a perspective view of the cover.

The fragmentary broken line showing of a speed changer housing is for illustrative purposes only.

I claim:

The ornamental design for a convectional cooling cover for mechanical speed changers and the like, as shown and described.
